UNITED STATES PATENT OFFICE.

JOHN C. MOSELEY, OF OAKLAND, MISSISSIPPI.

TAMPING-MACHINE.

SPECIFICATION forming part of Letters Patent No. 760,905, dated May 24, 1904.

Application filed March 4, 1904. Serial No. 196,637. (No model.)

To all whom it may concern:

Be it known that I, JOHN C. MOSELEY, a citizen of the United States, residing at Oakland, in the county of Yalobusha and State of Mississippi, have invented a new and useful Tamping-Machine, of which the following is a specification.

This invention relates to machines employed for mechanically tamping the ballast beneath the ties in railway construction, and has for its object to simplify and improve the construction and produce a device of this character of increased capacity and of more general application.

With these and other objects in view, which will appear as the nature of the invention is better understood, the same consists in certain novel features of construction, as herein-after fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages, and the right is therefore reserved of making all the changes and modifications which fairly fall within the scope of the invention and the claims made therefor.

In the drawings thus employed, Figure 1 is a plan view. Fig. 2 is a longitudinal elevation, partly in section. Fig. 3 is a transverse section.

The improved machine comprises a carriage 10, mounted to run upon the rails 11 12 on flanged wheels 13 and supporting a frame 14, spaced above the carriage by vertical members 15.

Spaced above the frame 14 is another frame 16, which will be designated the "tamper-carrying" frame, and mounted to move vertically upon guide members 17, extending at suitable points from the supporting-frame 14.

The frame 16 is provided with spaced aper-

tures 18 in each of its side members and in which the stocks of the tampers are pivoted, as at 20, with their lower ends formed with sockets 21, in which the tamper-feet 22 are secured rigidly when in use by set-screws 23. 55 By this means tamper-feet of different forms and sizes may be connected into the sockets when required.

Transversely disposed across the ends of the supporting-frame 14 are shafts 24 25, carrying cams 26 27 for engagement with rollers 36 on the frame 16 at its opposite ends. The cams are each formed with a plurality of faces, so that the frame 16 and its connected tampers will be elevated a number of times 65 at each revolution of the shaft, as will be obvious. The shafts are provided with operating-crank 28 29, and in order to cause the cams to operate simultaneously and in opposite directions and also to increase the steadiness of the motion a small counter-shaft 30 is provided and connected to be operated from the shaft 24 by gears 31 32 and connected to the shaft 25 by a chain 33 and chain-wheels 34 35. By this means it will be obvious that 75 the rotation of either or both of the shafts 24 25 will communicate motion to both ends of the frame 16 uniformly and steadily.

The frames and carriage portion may be constructed of wood or metal or partially of wood and partially of metal and of any desired size or form of construction.

The shanks 19 of the tampers will be provided with a plurality of spaced apertures 37 to receive the pivots 20, and thus provide 85 means for the vertical adjustment of the tampers.

Extending between the vertical members 15 and between the frame 14 and carriage 10 are members 38 39, upon which guide members 40 41 are adjustably supported by clamp-bolts 42 43, operating through slots 44 45 in the guide members and the connecting members 38 39. The guide members are provided with spaced recesses 46 47, in which the shanks 95 19 of the tampers operate. The guide members 40 41 are further supported by lateral brackets 48 49 and by larger recesses for embracing the vertical members 15.

By adjusting the guide members it is obvi-

100

ous the shoe portions 22 of the tampers may be correspondingly adjusted to conform to the widths of the ties 50, and thus adapt the machines to ties of varying widths.

- 5 The tamper members will be so located as to occupy the whole length of the tie upon each end and both inside and outside the rails 11 12, so that the whole area of the ballast upon each side will be tampered at the same 10 time and with uniformity, as the frame carrying the tampers is operated with corresponding uniformity, as before described. By this means the tamping can be accomplished very rapidly and the machine moved along the rails 15 from tie to tie as required.

When moving from place to place, the frame 16, carrying the tamper members, can be blocked up or supported in an elevated position to bring the shoes 22 above the rails.

- 20 Having thus described the invention, what is claimed is—

1. In a machine of the class described, a supporting structure mounted for movement along a railway-track, a frame mounted for 25 movement transversely of the plane of the track, means for reciprocating said frame, tampers pivotally mounted in said frame and partaking of its motion, and adjusting means for controlling the positions of the operative 30 ends of the tampers.

2. In a machine of the class described, a supporting structure mounted for movement along a railway-track, a frame mounted for movement transversely of the plane of the 35 track, means for reciprocating said frame, a plurality of tampers spaced apart and movably mounted in said frame and partaking of its motion, and adjusting means for controlling the positions of the operative end of said 40 tampers.

3. In a machine of the class described, a supporting structure mounted for movement along a railway-track, a frame mounted for movement transversely of the plane of the 45 track, means for reciprocating said frame, tampers pivotally mounted in said frame and partaking of its motion, and guide members having spaced recesses for receiving said tampers and adjustably supported upon said 50 structure for effecting the adjustment and guidance of said tampers.

4. In a machine of the class described, a

supporting structure for movement along a railway-track and having spaced vertical guides, a frame for movement upon said guides transversely of the plane of the track, shafts mounted for rotation upon said structure and provided with cams for engagement with said frame, and connecting means between said shafts whereby they are simultaneously rotated to cause said cams to simultaneously engage said frame.

5. In a machine of the class described, a supporting structure for movement along a railway-track and having spaced vertical guides, a frame for movement upon said guides transversely of the plane of the track, shafts mounted for rotation upon said structure and provided with cams for engagement with said frame, and a chain connecting said shafts for 60 effecting their simultaneous rotation.

6. The combination in a machine of the class described, of a supporting structure mounted for travel along a railway-track, a frame mounted for reciprocal movement in a plane 75 at right angles to said track, a plurality of oppositely-disposed tampers movably connected to said frame, adjustable guide members for receiving said tampers, and means for reciprocating said frame.

7. The combination in a machine of the class described, of a carriage mounted for travel along a railway-track, a frame spaced from said carriage and disposed transversely of the same and connected thereto by spaced vertical 85 members, a frame mounted for reciprocation above said transverse frame, means for actuating said reciprocating frame, tampers movably connected to said reciprocating frame, bars connecting said vertical members intermediate of said carriage and transverse frame, guide-plates having spaced recesses for receiving said tampers and provided with transverse slots through which clamp-bolts pass from said bars to effect the adjustment 90 of said guide-plates to control the positions of the operative ends of said tampers.

In testimony that I claim the foregoing as my own I have hereto affixed my signature in the presence of two witnesses.

JOHN C. MOSELEY.
